UNITED STATES PATENT OFFICE.

WINTHROP KEITH HOWE, OF ROCHESTER, NEW YORK, ASSIGNOR, BY MESNE ASSIGNMENTS, TO GENERAL RAILWAY SIGNAL COMPANY, OF ROCHESTER, NEW YORK, A CORPORATION OF NEW YORK.

CLOTHES CYLINDER FOR WASHING MACHINES.

Application filed August 25, 1921. Serial No. 495,350.

The present invention relates to clothes drums or cylinders for washing machines, and particularly to the type of clothes cylinders which are oscillated or rotated in a 5 suitable tub of water when in use.

Clothes cylinders or drums of this kind have commonly been made entirely of wood, because they are cheap, do not readily corrode, and are not affected by electrolytic 10 action. The wooden end walls, however, swell more transversely of the grain of the wood than with it and thereby warp out of shape, so that if the ends are made round at the start, they swell elliptical and sometimes 15 rub against the tub in cases where moderate clearances are allowed. The ends may be made elliptical initially so as to swell round when wet; but this is objectionable because it means the cylinder wobbles when 20 dry. Also, the fastening of the slats to the end walls constitute a source of trouble; and the slats may become loose in course of time due to the softening of the wood on account 25 of its continued exposure to moisture.

With the above considerations in mind, the objects of the present invention are to improve the construction of washing machine cylinders by choosing the material and construction best adapted for each part of 30 the cylinder. For instance, since the swelling and warping of the wood is particularly objectionable in the end walls, on account of the difficulty of running the grain of the wood uniformly in all directions, in accordance 35 with the present invention, metal is used for the end walls. On the other hand, it is preferred to use wooden slats for they are easily provided with openings to allow water to pass freely into and out of the 40 cylinder without leaving sharp and dangerous edges.

Another object of the present invention is to provide a cover for a clothes cylinder which is held against removal by the end 45 walls of the cylinder itself, rather than by some movable latch or fastening means which may loosen, or wear out, and give trouble.

Other objects and advantages of the invention will be apparent as the description progresses, and the novel features thereof will be particularly pointed out in the appended claims.

In describing the invention in detail, ref-

erence will be made to the accompanying drawings, in which:—

Fig. 1 is a transverse section through the cylinder, taken on the line 1—1, Fig. 2;

Fig. 2 is a longitudinal section taken on the line 2—2, Fig. 1; and

Fig. 3 is a fragmentary view of the cylinder particularly showing the cover, part of the end walls being cut away for clearness.

The particular embodiment of my invention illustrated, comprises in general two circular end walls or plates E formed with inwardly extending flanges 1, between which are riveted slats S of suitable material. The ends of the flanges 1 on these end walls are rolled to form a bead 1^a, thereby eliminating sharp edges that might injure the hands of the operator, or tear the clothes when filling the cylinder or wringing clothes therefrom. These end walls E are made of suitable sheet metal, such as steel which has been galvanized, or a non-corroding metal, such as aluminum, copper, nickelized zinc or the like, the metal used in the cylinder being selected with due regard to metal lining of the tub so as to avoid electrolytic action, caused by dissimilar metals in electrical contact and in an intervening electrolyte, such as water containing washing compound. At the center and on the outside of each end wall E is riveted a circular plate 2 having an integral bearing boss, one of these bearing bosses forming a socket, triangular, square, or otherwise polygonal in cross section to receive a similar shaped driving member of the operating mechanism of the washing machine (not shown). The other bearing boss is intended to be supported by a journal of suitable construction.

The slats S are preferably made of wood, although metal slats may be used if desired. The usual holes 3 for water to pass through the slats are formed with rounded edges. These slats are riveted to the flanges 1 on the inside, with spaces between, as shown, for about 5% around the circumference, the remaining space constituting the opening for putting clothes into and out of the cylinder. For the purpose of reinforcing the cylinder, and particularly to prevent bending and warping of the slats, a reinforcing strip 4 of metal is preferably riveted to the middle of the slats on the outside.

Spaced around the inside of the cylinder

are several clothes lifters 5, five being shown in this instance. These lifters serve to lift the clothes up and drop them back into the water as the cylinder is rotated or oscillated.

5 They are fastened to the end walls and reinforcing band by wood screws, as shown.

The cover C for the cylinder comprises several slats, secured together by three straps 6—6 and 7 of metal riveted thereto, to form

10 a panel of the same curvature as the cylinder. The two straps 6—6 near the ends of the cover extend at each end beyond the edges of the cover so as to engage the slats on each side of the opening, and thereby

15 prevent the cover dropping into the cylinder. The slats of the cover C are cut a little shorter than the distance between the end walls E, so that if one end of the cover is pushed fully back under the flange 1 of

20 one end wall, the other end may pass by the flange 1 of the other end wall. To maintain the cover C midway between the end walls, flat springs 8 are riveted to the outside of the end walls, and to the outer ends of these

25 springs are riveted studs 9 which extend through holes in the end walls and to which shoes 10 are fastened. These shoes 10 bear against the opposite ends of some of the slats of the cover, thereby maintaining the

30 cover in position below or behind the flanges of both end walls. Curved brackets 11 are riveted to the end walls E of the cylinder adjacent the opening to guide and support the cover C as it is put in place.

35 The cover C is placed on the cylinder by inserting one end of the cover between the flange 1 and bracket 11 of one end wall E, hand holes 12 being provided to enable the cover to be conveniently handled; and the

40 cover is then forced endwise, pushing back the shoes 10 at that end of the cylinder, until the other end of the cover can move in past its co-operating flange 1. When the cover is released, the springs 8 will force

45 it to its middle position, where it is held against outward movement by the flanges 1 and against inward movement by its end straps 6—6.

Having now fully described one specific

50 embodiment of my invention, what I desire to secure by Letters Patent is:—

1. A washing machine cylinder comprising, two circular metallic end walls, a peripheral wall connecting said end walls and extending only part way around the edge of said walls to form a cylinder having a large opening, a cover for said opening, and means for maintaining said cover in a predetermined relation with said end walls including means extending through a small opening in an end wall, and a flat spring fastened to the end wall for urging said means into said small opening.
2. A washing machine cylinder comprising, two circular metallic end walls, a per-

ipheral wall joining said circular walls and extending only part way around these walls to form a cylinder having a large opening, and cover spacing means extending through a small opening in one of said walls forced 70 inwardly by a flat spring riveted to said end wall for engaging a cover for said large opening.

3. An end wall for washing machine cylinders comprising, a circular metallic wall 75 having a small opening near the periphery thereof, a peripheral flange extending at right angles to said end wall for securing a cylinder thereto, and resilient spacing means including a flat leaf spring riveted to said circular wall, and a plunger fastened to said spring and extending through said small opening for maintaining a portion of said cylinder in engagement with said peripheral flange.

4. An end wall for washing machine cylinders comprising, a circular metallic wall having a small opening near the periphery thereof, a flange extending at right angles to said end wall, a cylinder secured to said flange, and means for maintaining a portion of said cylinder in engagement with said flange comprising a flat spring riveted to said circular wall so that its end overlies said small opening, and a plunger fastened to said spring through said small opening having an enlarged portion at the free end thereof so that said spring can be bent from said circular wall a limited distance only.

5. A washing machine cylinder comprising, two circular metallic end walls, a peripheral wall joining said end walls to form a cylinder having a large opening, a cover for said opening, and means for holding said cover in a predetermined position including a flat spring riveted to one of said walls having its free end overlying a small opening in said wall, and a plunger fastened to said spring and passing through said small opening and having an enlarged portion at its free end, whereby the plunger may be withdrawn only a limited distance from said small opening.

6. A washing machine cylinder comprising, two circular end walls terminating in beads extending about the periphery of said walls, a peripheral wall joining said end walls to form a cylinder having a large opening, a small opening in one of said end walls adjacent said large opening, and a spring pressed plunger extending through said small opening for holding a cover for said large opening in a predetermined position.

7. A clothes cylinder for washing machines 125 having an opening and provided with a cover slightly larger than said opening, and resilient means connected to the cylinder proper for yieldingly maintaining said cover in said opening.

8. A washing machine cylinder having an opening, pockets facing each other on opposite ends of the opening, a cover having ends adapted to fit in said pockets, and spring means for yieldingly maintaining said cover in a middle position with its ends in said pockets.

9. A washing machine cylinder having an opening and provided with inwardly extending flanges opposite said opening, a cover having ends adapted to fit under said flanges, means for preventing the cover from falling into said drum, and resilient means connected to the ends of the cylinder for yieldingly maintaining said cover in a middle position.

10. A washing machine cylinder comprising, sheet metal end walls with inwardly projecting flanges, wooden slats fastened to said flanges on the inside part way around the cylinder to leave an opening for the insertion and withdrawal of the clothes, a cover for the opening comprising similar slats whose ends are adapted to fit under said flanges, straps fastened to the outside of the slats of

the cover and having projecting ends adapted to engage the slats adjacent the opening, and springs for yieldingly maintaining the cover in the middle position with its ends behind said flanges.

11. A washing machine cylinder comprising, metallic flanged end walls provided with holes adjacent said flanges, a cover in overlapped relation with both of said flanges, and spring-pressed members extending through said holes for maintaining said cover in such overlapped relation.

12. A washing machine cylinder comprising, metallic flanged end walls provided with holes adjacent said flanges, a cover in overlapped relation with both of said flanges, means for supporting the cover against inward movement, and spring-pressed means extending through said holes for maintaining said cover in its middle position.

In testimony whereof I hereby affix my signature.

WINTHROP KEITH HOWE.
